No. 608,580.

Patented Aug. 9, 1898.

J. T. COWLEY.
CONVEYING APPARATUS.

(Application filed Feb. 17, 1898.)

(No Model.)

Witnessed: Inventor:

UNITED STATES PATENT OFFICE.

JAMES T. COWLEY, OF LOWELL, MASSACHUSETTS, ASSIGNOR TO THE LAMSON CONSOLIDATED STORE SERVICE COMPANY, OF NEWARK, NEW JERSEY.

CONVEYING APPARATUS.

SPECIFICATION forming part of Letters Patent No. 608,580, dated August 9, 1898.

Application filed February 17, 1898. Serial No. 670,622. (No model.)

To all whom it may concern:

Be it known that I, JAMES T. COWLEY, of Lowell, in the county of Middlesex and State of Massachusetts, have invented certain new and useful Improvements in Conveying Apparatus, of which the following is a specification.

My invention relates to improvements in conveying apparatus, and especially to that class of conveying apparatus known as "cable-carriers."

The object of my invention is to provide means on the several tracks converging at the terminal station in order that carriers belonging to a certain track can engage only the propelling-cable of said track when placed thereon at the terminal station and be propelled to the station to which they belong.

My invention consists of certain novel features hereinafter described, and particularly pointed out in the claims.

In the accompanying drawings, which illustrate a construction embodying my invention, Figure 1 represents a side view in perspective of a line which is composed of an upper and a lower track entering the terminal station and representing a carrier placed upon the upper return-track and showing the gripping mechanism on the carriers operated by the grip-operating mechanism to open the jaws preparatory to gripping the cable. Fig. 2 is a perspective view of part of the apparatus shown in Fig. 1 and illustrating the carrier moved forward of the position shown in Fig. 1, with the jaws of the gripping mechanism around the cable preparatory to gripping the same. Fig. 3 is a detail side view of part of the apparatus shown in Fig. 1 and looking from the opposite side to that shown in Fig. 1. Fig. 4 illustrates a portion of the view shown in Fig. 3 with the cable pulled downward from its normal position. Fig. 5 is an end view in perspective, looking at the front end of the carrier.

Like letters of reference refer to like parts throughout the several views.

The return-track A is composed of the two opposite rails A', which are supported and firmly secured to the standard B at the terminal station. The rails A' near the stand-

ard B are spread out of a straight line to form the opening A² at which point the carrier is applied to the return-track to be propelled to the salesman or clerk from whom it came. The carrier is adapted to engage with the cable E, running over the pulleys C, mounted in the lugs D of the standard B and connected to and driven by suitable driving mechanism. The carrier F is provided with a cover F', held in a closed position by a suitable spring-catch, which upon being operated by the push-button F² releases the cover F', and the spring F³ will throw up the cover F' and open the interior of the carrier.

F⁴ represents suitable switching pins or lugs on the carriers by means of which the carriers are switched at their respective stations. These lugs are placed in different positions on the carriers to correspond with switch-guides at different stations along the line, so that the carriers may be switched at the stations to which they belong.

The lever G is provided with a pin G', upon which the gripping-jaws G² are pivotally mounted, and said lever is journaled in the lugs G³ on the rear side of the carrier. These jaws G² are each provided with a cam-slot G⁴, (see Fig. 5,) which work upon the stud G⁵, secured to the end of the carrier, and said cam-slots G⁴ are of such form that the jaws will be opened as the lever G is lowered in position to cause the jaws G² to engage with the cable E. (See Fig. 1.) When the lever G is released from its downward position, the spring G⁶, located at the back of the carrier and around the lever G, will operate to raise said lever and close the jaws G² on the propelling-cable E.

The construction of the jaws above described and the lever for operating the same form no part of this invention, as the same is shown, described, and claimed in United States Letters Patent issued to the Lamson Consolidated Store Service Company, of Newark, New Jersey, as my assignee, on January 5, 1897, and numbered 574,715.

H is a plate secured to the bottom of the carrier by screws H', and said plate is provided with ears H², which are adapted to pass under the rails A' of the track A and hold the

carrier thereon, as said ears extend beyond said rails A' , excepting where said rails are bulged at A^2 to permit the carrier being placed thereon. H^3 represent friction-rollers mounted upon the screws H' and free to revolve thereon, and the object of these rollers is to prevent friction as the carrier is traveling along the track, around the corners, and into the stations.

10 On the extension K of the brace J there is pivoted on the pin L' the cam-plate L near the standard B , and said cam-plate is held in its operative position (see Fig. 3) by the spring L^2 , which at its free end bears against the pin L^3 on said plate and holds said plate upwardly and at its other end is secured to the extension K by bolts L^4 . The cam-plate L in its movements is guided by the pin L^5 , working in the slot L^6 on the extension K . When a 15 carrier has been placed on the wrong track and has been pushed beyond the cam-plate and the grip has closed without taking up the cable, said carrier can be moved rearwardly, with the lever G moving along the 20 upper edge of the cam-plate, and said plate will yield and allow the carrier to be moved rearwardly and to be taken from said track and placed upon its proper track. To the 25 lower end and on the inner side of said extension K there is pivotally mounted at M' the arm M , having a slot M^2 in its upper edge, and to said arm M at M^3 there is pivotally secured the rod N , which rod, extending rearwardly in the direction of the standard B , is 30 pivotally connected at O' to the arm O , secured fast on the shaft P' , journaled in the lugs P^2 of the rail-brace P . Secured fast on said shaft P' by a suitable sleeve Q is a hook Q' , the upper end of which extends over the 35 cable E , as shown.

A number of lines similar to that illustrated enter the terminal station, and if the cashier in returning the carrier to the clerk or salesman from whom it came should place it on 40 the track to which it belongs the pin G^7 of the lever G will register with the slot M^2 of the arm M , as shown in Fig. 2, and as the lever G passes beyond the end of the cam-plate L the lever G will move up by reason of 45 the spring G^6 , and the jaws G^2 , being around the cable E , will grip the same and the carrier will be propelled on the track to the salesman from whom it came.

If the carrier should be placed on the wrong 50 return-track and is pushed forward by the cashier, as is the case in all cable systems, until the grip engages the cable, the pin G^7 will not register with the slot M^2 on said track, but will bear against the upper end of said 55 arm M and move it from its vertical position (shown in Figs. 1 and 2) to that shown in Fig. 4, in which position it will be seen that the pin G^7 , having moved the arm M to a slanting position, as shown, will pass over the upper 60 edge thereof; but in moving said arm to said slanting position the rod N , connected to said arm M , will pull the arm O to the position 65

shown in Fig. 4, and said arm O , being fast on the shaft P' , will cause said shaft to move, and with it the hook Q' will move to the 70 position shown in Fig. 4, thereby pulling the cable E from its normal position, as shown in Figs. 1, 2, and 3, to that shown in Fig. 4.

It is obvious that as the lever G passes under the end of the cam-plate L and moves 75 upwardly by reason of the spring G^6 , as shown in Figs. 1 and 2, the jaws will not close upon the cable E , as said cable has been pulled from its normal position between the jaws, as shown in Figs. 1 and 2, to that shown in Fig. 80 4 and consequently the carrier will not be propelled along the track. In this case the cashier will remove the carrier and place it upon its proper return-track, when the pin G^7 will pass through the slot M^2 and the cable 85 will be gripped by the gripping-jaws G^2 , as hereinbefore described, and the carrier will be propelled to the station from which it came.

The carriers are sent to the terminal or 90 cashier's station from the salesmen's stations on the lower forwarding-track S , composed of the opposite rails S' , and said rails are bulged at S^2 , the same as the track A at A^2 , in order to allow the carriers to be removed, as the 95 distance between the rails S' at S^2 is greater than the distance between the ears H^2 of the plate H , secured to the bottom of the carrier. The rods S^3 , located on opposite sides of the rails S' , serve to keep the carriers on the forwarding-track as they pass into the terminal or cashier's station.

S^4 represents a suitable bumper against which the carriers strike when coming in on the return-track S , and S^5 is a suitable brace 105 connecting the rails S' and holding them in their proper positions.

It will be understood that the pins G^7 and the slots M^2 are so arranged that the pin G^7 on the carriers belonging to a certain track 110 will register with the slot M^2 of the arm M of said track, so that the gripping mechanism of the carriers belonging to a certain track will grip only the cable of said track.

From the above description it will be understood that although several cable-lines, 115 each composed of an upper and lower track and similar in construction with the exception of the location of the slot M^2 , enter the terminal station from different parts of the 120 store, yet by the mechanism above described should the carriers become mixed at the terminal station and be placed on the return-track of the wrong line the gripping mechanism of the carriers wrongly placed will not 125 grip the cable of said line and be propelled thereon, as hereinbefore described. Consequently the carriers running into the terminal or cashier's station on the several tracks 130 can only be propelled on the tracks to which they belong to the station from which they were received.

I do not limit myself to the arrangement and construction shown, as the same may be

varied without departing from the spirit of my invention.

Having thus ascertained the nature of my invention and set forth a construction embodying the same, what I claim as new, and desire to secure by Letters Patent of the United States, is—

1. In a conveying apparatus, the combination of a forwarding and a return track and propelling-cable with a terminal station into which the tracks enter, carriers adapted to travel on said tracks each provided with a gripping mechanism for engaging the cable, grip-operating mechanism on the return-track at said terminal station, and mechanism at said terminal station in position to engage the cable, the gripping mechanism on the carrier belonging to a certain track and the said cable-engaging mechanism of said track being provided with registering parts whereby only carriers belonging to a certain track can grip the cable of said track and be propelled thereon.
- 15 at said terminal station, and mechanism at said terminal station adapted when actuated by the movement of a carrier placed on the wrong return-track to engage and remove the propelling-cable away from engagement with the gripping mechanism of the carrier.
- 20 2. In a conveying apparatus, the combination of a forwarding and a return track and

propelling-cable with a terminal station into which the tracks enter, carriers adapted to travel on said tracks each provided with a gripping mechanism for engaging the cable, grip-operating mechanism on the return-track at said terminal station, and mechanism at said terminal station in position to engage the cable, the gripping mechanism on the carrier belonging to a certain track and the said cable-engaging mechanism of said track being provided with registering parts whereby only carriers belonging to a certain track can grip the cable of said track and be 35 propelled thereon.

In testimony whereof I have signed my name to this specification, in the presence of two subscribing witnesses, this 8th day of February, 1898.

JAMES T. COWLEY.
